STUFFED TOY

Terrance R. Mitchell, Bloomington, Minn., assignor to Spectacular Products, Inc., Cannon Falls, Minn., a corporation of Minnesota

Filed Feb. 3, 1966, Ser. No. 910

Term of patent 14 years

(Cl. D34—2)

FIG 1

FIG 8

FIG. 1 is a perspective view of a stuffed toy embodying my design;

FIG. 2 is a front elevational view thereof;

FIG. 3 is a side elevational view thereof;

FIG. 4 is a rear elevational view thereof;

FIG. 5 is a top plan view thereof;

FIG. 6 is a bottom plan view thereof;

FIG. 7 is a perspective view thereof with the ear portions in extended positions; and

FIG. 8 is a perspective view of the form shown in FIGS. 1-6 inclusive in inverted position.

The side opposite that shown in FIG. 3 is substantially a mirror image thereof.

I claim:

The ornamental design for a stuffed toy, as shown and described.
